(57) **CLAIM**

The ornamental design for a light bulb, as shown and described.

DESCRIPTION

FIG. 1 is a perspective view of a light bulb showing our design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a perspective view of another light bulb showing our design;

FIG. 9 is a top view thereof;

FIG. 10 is a bottom view thereof;

FIG. 11 is a front view thereof;

FIG. 12 is a rear view thereof;

FIG. 13 is a left side view thereof;

FIG. 14 is a right side view thereof;

FIG. 15 is a perspective view of another light bulb showing our design;

FIG. 16 is a top view thereof;

FIG. 17 is a bottom view thereof;

FIG. 18 is a front view thereof;

FIG. 19 is a rear view thereof;

FIG. 20 is a left side view thereof;

FIG. 21 is a right side view thereof;

FIG. 22 is a perspective view of a light bulb end cap showing our design;

FIG. 23 is a front view thereof; rear and side views being identical thereto;

FIG. 24 is a top view thereof;

FIG. 25 is a bottom view thereof;

FIG. 26 is a perspective view of another light bulb showing our design;

FIG. 27 is a top view thereof;

FIG. 28 is a bottom view thereof;

FIG. 29 is a front view thereof;
FIG. 30 is a rear view thereof;
FIG. 31 is a left side view thereof;
FIG. 32 is a right side view thereof;
FIG. 33 is a perspective view of another light bulb end cap showing our design;
FIG. 34 is a front view thereof; rear and side views being identical thereto;
FIG. 35 is a top view thereof;
FIG. 36 is a bottom view thereof;
FIG. 37 is a perspective view of another light bulb end cap showing our design;

FIG. 38 is a front view thereof;
FIG. 39 is a rear view thereof;
FIG. 40 is a right side view thereof;
FIG. 41 is a left side view thereof;
FIG. 42 is a top view thereof; and,
FIG. 43 is a bottom view thereof.
The broken lines herein show environmental structure and form no part of the claimed design.

UNITED STATES PATENT AND TRADEMARK OFFICE
CERTIFICATE OF CORRECTION

PATENT NO. : D700,719 S
APPLICATION NO. : 29/415316
DATED : March 4, 2014
INVENTOR(S) : Jeffery R. Parker, James T. Petroski and Witold Bauer

Page 1 of 2

It is certified that error appears in the above-identified patent and that said Letters Patent is hereby corrected as shown below:

Delete title page and Page 2 showing additional related descriptions and substitute therefore with the attached title page consisting of the corrected number of Drawing Sheets in patent.

In the Drawings

Delete Drawing Sheets 19-30, Figures 22-43 should be removed and also the related descriptions.

Signed and Sealed this
Twentieth Day of January, 2015

Michelle K. Lee
Deputy Director of the United States Patent and Trademark Office
